US00D822645S

(12) **United States Design Patent** (10) Patent No.: **US D822,645 S**
(45) Date of Patent: ** *Jul. 10, 2018

(54) **HEADPHONE**

(71) Applicant: **BRAGI GmbH**, München (DE)

(72) Inventor: **Arne D Loermann**, München (DE)

(73) Assignee: **BRAGI GmbH**, München (DE)

(*) Notice: This patent is subject to a terminal disclaimer.

(**) Term: **15 Years**

(21) Appl. No.: **29/576,545**

(22) Filed: **Sep. 3, 2016**

(51) LOC (11) Cl. **14-01**

(52) U.S. Cl.

USPC **D14/223**

(58) **Field of Classification Search**

(57) **CLAIM**

The ornamental design for a headphone, as shown and described.

DESCRIPTION

FIG. 1 is a perspective view of a headphone in accordance with the present invention;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken lines in the Figures show portions of the headphone and environment which form no part of the claimed design.

1 Claim, 2 Drawing Sheets
